UNITED STATES PATENT OFFICE.

JOHN A. MAUCK, OF PRINCETON, INDIANA.

CARBURETER.

1,288,639.

Specification of Letters Patent. Patented Dec. 24, 1918.

Application filed September 10, 1917. Serial No. 190,581.

To all whom it may concern:

Be it known that I, JOHN A. MAUCK, a citizen of the United States, residing at Princeton, in the county of Gibson and State of Indiana, have invented certain new and useful Improvements in Carbureters; and I do declare the following to be a full, clear, and exact description of the invention, such as will enable others skilled in the art to which it appertains to make and use the same.

My invention relates to improvements in carbureters and more particularly to those which are intended for mixing steam mixed with air with the mixture of fuel and air drawn from the device by the suction caused by the engine pistons. I am aware that numerous types of carbureters have heretofore been devised for carrying out this end, but the object of the present invention is to provide a device of this class which may be constructed easily and inexpensively and at the same time result in an extremely efficient means for producing the desired result.

With the foregoing general object in view, the invention resides in the novel features of construction and unique combinations of parts to be hereinafter fully described and claimed, the descriptive matter being supplemented by the accompanying drawings which form a part of this specification and in which:

Figure 1 is a vertical section of the improved carbureter;

Figs. 2, 3 and 4 are horizontal sections on the planes of the lines 2-2, 3-3 and 4-4, respectively, of Fig. 1, looking in the directions indicated by the arrows;

Fig. 5 is a vertical transverse section on the plane indicated by the line 5-5 of Fig. 1; and

Fig. 6 is a detail longitudinal section similar to the upper portion of Fig. 1, but illustrating a modified form of construction.

In the drawings above briefly described, the numerals 1 and 1' designate respectively a fuel reservoir and a water reservoir, the two being preferably, though not necessarily, cast integrally as shown clearly in Fig. 1. The inlets of the reservoirs 1 and 1' are provided with any appropriate type of constant level device such as the float controlled valves 2 and 2', and in order that either gasolene or kerosene may be fed to the reservoir 1, as occasion may demand, a pair of supply tubes 3 and 4 are provided,

either one of which may be placed in communication with the main inlet tube 5, by means of a three-way valve 6. In most instances gasolene will be used as the fuel in starting, and until the engine has been heated to such a degree as to allow kerosene to be readily employed. When this degree of heat is obtained, however, the valve 6 is operated so that kerosene, or any other rather heavy oil, may be supplied to the chamber 1.

Air passages 7 and 7' lead vertically through the two reservoirs 1 and 1' respectively, suitable nozzles 8 and 8' being positioned in said passages for supplying a spray of liquid thereto as suction is created through said passages by the action of the engine, it being obvious that since said nozzles communicate respectively with the reservoirs 1 and 1', they will supply the passage 7 with fuel, whereas the passage 7' will be furnished with a spray of water. The upper ends of the passages 7 and 7' deliver into a pair of tubular perforated outlet members 9 and 9' which rest upon a horizontal plate 10 which is secured over and closes the upper ends of the reservoirs, the member 9' being preferably of less size than the member 9 since less water than fuel is to be handled by the device.

A peripheral wall member 11 rests on the plate 10 and is suitably secured thereto, said wall member having a transverse partition 12 which divides the space circumscribed by said member, into a pair of heating chambers 13 and 13' adapted respectively to heat the fuel from the passage 7 and to convert the water vapor and air from the passage 7' into a mixture of steam and air. Any preferred type of heating device could well be employed, but I preferably provide a flat pipe 14 extending through both chambers 13 and 13' and having means at its ends for connecting it to the usual or any preferred type of exhaust manifold, so that the hot gases passing through said pipe will perform the heating function effectively. Around the outlet members 9 and 9', the pipe 14 is provided with an annular series of 105 preferably V-shaped heat radiating webs 15 between which and other oblique webs 15', on the sides of the pipe 14, the fuel mixture and the mixture of water vapor and air must pass from said outlet members, before 110 traveling to the upper ends of the chambers 13 and 13', from which the mixtures formed

are withdrawn. The upper side of the flat pipe 14 will also in most cases be provided with heat radiating webs 16 which are preferably arranged as depicted in Fig. 2, although any other suitable disposition could well be utilized. A top plate 17 closes the upper ends of the chambers 13 and 13' and is rigidly secured in place in any preferred manner, said plate having an outlet opening 18 leading from the chamber 13, and a similar opening 18' which communicates with the chamber 13'. A suitable dome 19 rests on and is secured to the plate 17, said dome extending over both openings 18 and 18' and having a short vertical discharge pipe 20 which registers with the opening 18 as shown clearly in Fig. 1, said pipe being adapted for attachment to the intake manifold 21 and having one or more openings 22 for admitting the mixture of steam and air collecting in the dome as it is discharged from the chamber 13', through the outlet opening 18'. The openings 22 are preferably though not necessarily positioned on tangential lines as indicated in Fig. 3, so that the mixture entering the outlet pipe 20, is whirled around to insure thorough mixing thereof with the volatile mixture rising through said pipe from the chamber 13.

30 A high speed air inlet 23 is provided in the dome 19 for supplying an auxiliary quantity of air to the passage 20 when the engine runs faster than a pre-determined speed. The air from the inlet 23 may be 35 allowed to mingle with the mixture in the dome 19, by the provision of a construction such as that illustrated in Fig. 6, or a horizontal partition 24 may be provided in said dome, so that the mixture will be confined 40 beneath this partition, whereas the air coming into the intake 23, will flow between the partition and the top of the dome, and will enter the pipe 20 through perforations 25 spaced above the perforations 22 above described. Either construction is highly efficient and I merely illustrate both to disclose the two ways of obtaining the required result.

The improved carburetor is installed by 50 connecting its outlet pipe 20 with the intake manifold 21, and connecting its exhaust pipe 14 with the exhaust manifold of the engine, as will be clear from Fig. 1. Either 55 gasoline or oil will now be supplied to the reservoir 1 through the tubes 3, 4 and 5, and the valve 6, and the constant level device will cut off the supply at the valve 2, when it has risen to the required level in the nozzle 8. Similarly, water is supplied to 60 the reservoir 1' through the inlet pipe 5', and the automatic regulating means of the valve 2' cuts off the supply, when the water level has risen to the required extent. In 65 starting the motor, gasoline will in most cases be fed to the reservoir 1 to insure easy

starting, but after the motor is running under its own power, valve 6 is operated and the oil supply tube may be utilized for feeding kerosene or the like to said reservoir. It will be obvious that the action of the pistons will draw a mixture of fuel and air through the passage 7, around the then heated exhaust pipe 14, and out the pipe 20 into the manifold 21, and similarly that a mixture of air and water vapor will be 70 drawn from the passage 7' into contact with the hot pipe 14, so that this mixture is converted instantaneously into a mixture of air and steam, which passes into the dome 19 and then enters the pipe 20 through the perforations 22 provided for this purpose. Since the mixtures of air and fuel and air and steam enter the pipe 20 at substantially the same point, an effective mixing takes place, particularly in view of the tangential 85 arrangement of the perforations 22, and a highly volatilized mixture is thus insured which will operate the motor to great advantage.

Preferably used in connection with the 90 features above described, is the usual choke valve 26 for the passage 7, and a similar valve 26' for the passage 7'. It may be necessary to use both of these chokes when starting, but in most cases it will only be 95 necessary to operate the valve 26', in order that water may not be drawn into the intake manifold and mixed with the gasoline, since this would cause a low grade fuel before heating of the exhaust pipe. After 100 this heating takes place, however, the choke 26' may again be opened, together with the valve 26, if the latter has been closed, so that the fuel, whether the latter be gasoline or oil, will be supplied with a quantity of 105 steam and air mixture for producing the well known results, such as increasing the power of the motor and minimizing carbon deposits.

From the foregoing, taken in connection 110 with the accompanying drawings, it will be obvious that although the improved carburetor is of comparatively simple and inexpensive construction, it will be highly efficient and durable. Since probably the best 115 results are obtained from the specific details shown and described, these features are by preference employed, but I wish it understood that within the scope of the invention as claimed, numerous minor changes 120 may well be made.

I claim:

1. In combination with a horizontal pipe through which a heating medium passes, a pair of independent heating chambers 125 through which said pipe extends, said heating chambers being disposed side by side and each having an outlet opening in its top and an inlet opening in its bottom, float-controlled water and fuel reservoirs beneath 130

- 5 said heating chambers, independent passages through said reservoirs to said inlet openings of the heating chambers, the lower ends of said passages having valved air in-
lets, nozzles for delivering fuel and water from said fuel and water reservoirs into their respective passages, a main outlet passage leading from the outlet opening of the fuel heating chamber for attachment to the
10 intake manifold of an internal combustion engine, said main outlet passage having perforations in its wall, and a moisture and air outlet passage extending along the tops of said heating chambers from the outlet of
15 the moisture heating chamber, the perforated part of said main outlet passage extending through said moisture and air outlet passage to receive a mixture of moisture and air therefrom.
20 2. In a carbureter, the combination of a fuel and a water reservoir having constant level devices, independent air passages through said reservoirs, spray nozzles for supplying fuel from said fuel reservoir into
25 one of said passages and water vapor from said water reservoir into the other passage, independent water vapor and fuel heating chambers into which said passages discharge respectively, a common outlet passage for
30 said chambers adapted for connection to the intake manifold of an engine, and heating means disposed in said chambers.
3. In a carbureter, the combination of a fuel and a water reservoir having constant level devices, air passages through said reservoirs and discharging at the upper ends thereof, spray nozzles for supplying fuel from said fuel reservoir into one of said passages and water vapor from said water
- 35 reservoir into the other passage, a pair of independent chambers into which said passages discharge said chambers having outlet openings in their upper ends, an outlet pipe leading from the outlet opening of one chamber and adapted for connection with the intake manifold of an engine, a water vapor passage leading from the outlet opening of the other chamber and discharging into said outlet pipe, and a pipe extending across said chambers and adapted to conduct the exhaust gases from the engine.
4. In a carbureter, the combination of a fuel and a water reservoir having constant level devices, air passages through said reservoirs and discharging at the upper ends thereof, spray nozzles for supplying fuel from said fuel reservoir into one of said passages and water vapor from said water reservoir into the other passage, a wall member resting on and secured to the top of said reservoirs, said wall member having a transverse partition dividing the space circumscribed thereby into two chambers into which said passages discharge, a top member resting on said wall member and secured thereto, said top member having a pair of openings forming outlets from said chambers, a dome resting on and secured to said top member, said dome extending over said outlet openings and having an outlet pipe communicating with one of said openings, said outlet pipe having a perforated portion positioned in said dome, and heating means in both of the aforesaid chambers.
In testimony whereof I have hereunto set my hand.

JOHN A. MAUCK
